Paul Hahn

UNITED STATES PATENT OFFICE

PAUL HAHN, OF BERLIN, GERMANY

LACE AND LIKE FASTENING

Application filed February 20, 1930, Serial No. 430,072, and in Germany September 8, 1928.

Lace fasteners for corsets, foot-wear and the like in the form of plates having apertures through which the lace can be threaded, are already known. These fasteners,

5 particularly after some use, are not quite reliable in that they allow the laces to slip and get loose.

The object of the present invention is to produce a fastener which remains permanently reliable, and the invention consists 10 in the provision of a plate having one or more clamping slits which are narrower than the thickness of the lace and one or more gateways opening at an angle into said 15 slits for leading the lace ends into the latter.

Being narrower than the thickness of the lace, the slits will cause the lace to be gripped and to be effectively prevented from slipping under the ordinary stress to which 20 the lace is exposed. This is particularly the case with elastic laces which are stretched on introduction into the clamping slits and which thereupon tend to regain their normal thickness, thereby building up a ridge 25 of material against the edges of the slit.

The fastening may be made still more secure by the provision of one or more apertures through which the lace can be threaded before it is introduced into the slits. In 30 this case the lace will withstand considerable forces.

Two sets of gateways and clamping slits may be provided, one for each end of the same lace or for connecting parts of different laces, and the plate itself may be given various forms, some of which are illustrated by way of example in the accompanying drawings.

Figs. 1 to 7 of the accompanying drawings 40 represent views of different forms of the fastening plate according to the invention,

Fig. 8 is a cross-section of a plate provided with a cover,

45 Fig. 9 is a plan of this plate in open position,

Fig. 10 is a cross-section of a covered plate of modified construction,

50 Fig. 11 is a plan of this form shown in open position,

Fig. 12 is a cross-section of a further modification of a covered plate,

Fig. 13 is a plan of the latter in open position,

Fig. 14 is a view of an annular form of 55 the device,

Fig. 15 is a cross-section on the line 15-15 of Fig. 14 on a reduced scale, and

Fig. 16 is a view of a modification of the 60 annular form.

The plate *p* is formed with one or more clamping slits *b* which are narrower than the thickness of the lace so that the latter, on being introduced into the slits will be retained therein and prevented normally 65 from slipping. For introducing the lace into the slit, a gateway *a* is provided which is formed with a flared mouth so that the lace will be readily admitted. The gateway opens at an angle into the slit *b*, preferably 70 at the centre of the latter so as to form a T, and the lace can then be introduced into either branch of the slit *b*. Alternatively two lace ends may be introduced one in each branch of the slit. Two or more sets of 75

slits and gateways may be provided in the same plate for receiving different parts of the same lace or for connecting the ends or parts of different laces. Such an arrangement is shown in Fig. 2 wherein the plate is 80 of a round construction. The plate in Fig. 1 is also of round construction; it has only one clamping slit and gateway but it has also an aperture *c* through which the lace can be threaded before or after its introduction into the slit so as to render the fastening more secure.

The entrance to the gateway may be disposed at the edge of the plate as shown in Figs. 1 and 2, but it can also be formed 90 by an aperture *d* in the body portion of the plate as shown in Fig. 3 and in various other figures. In Fig. 3 the aperture *d* provides the entrance for two sets of slits and gateways. The plate is moreover elongated and 95 has two additional lace apertures *c* one for each set of clamping slits. Fig. 4 shows another form of plate with two sets of clamping slits and additional lace apertures. More than one additional aperture may be pro- 100

vided for each set of clamping slits as shown in Figs. 5 and 6. The application of the lace to a plate of this type is illustrated by way of example in Fig. 6. One end of the lace is threaded through apertures *c* and *e* and then introduced into the slit *b*. The other end is threaded first through the aperture *c*, then introduced into the slit, thereupon threaded through the aperture *e*, and finally tucked under the lace portion passing from *c* to *b*. Where the slits and gateways form a T shape, the two branches of the clamping slit *b* may be utilized for both ends of the lace. This is also shown in Fig. 6.

Fig. 7 shows an arrangement with three auxiliary lace apertures *c*, *e* for each end of the lace and where the ends of two laces are connected together, one of the ends may be attached merely to the aperture *c*, *e*, as shown in this figure.

A dished plate *p'* may be employed as shown in Figs. 8 and 9 and connected by a hinge *g* to a companion plate *f* serving as a cover for the fastener and forming a sort of button. In this case both plates may be provided with clamping slits as well as with one or more lace apertures *c*. The free ends of the lace may be enclosed between the plates or extended through apertures or slits in the plates. The entrance to the gateway may be at the edge of the plate or formed by an aperture *d* as shown.

These slits and apertures may be made in a depressed portion *l* of the plate *p'* as shown in Figs. 10 and 11.

Figs. 12 and 13 also show a construction presenting two dished, hingedly-connected plates *p'*, *f*, but the clamping slits are here made in a plate *h* which is connected to the plate *p'* and set off from the latter by a space *i*. The additional lace aperture is moreover fitted with a flanged eyelet *c'* which also serves as a connecting element for the plate *h*.

The plate may be formed into a ring or sleeve as shown in Figs. 14 to 16 which also show different formations of slits and apertures. One end of the ring or sleeve may be closed so as to form a box.

When the slits *b* are shown at right angles to the gateway, the angle may be varied according to requirements.

The branches of the slits *b* must be at least as long as the lace is wide, but they are preferably made much longer. The apertures *c*, *e* should be substantially of the same width as the lace.

The plates may be made of any suitable material such as horn, celluloid, vulcanite, metal or the like.

I claim:—

1. A lace and like fastening comprising two hingedly connected plates one of which has a straight clamping slit that is narrower than the thickness of the lace, a gateway for the lace leading at right angles into said slit at a point situated midway between the ends thereof, and an aperture through which the lace can be threaded, said aperture situated in alignment with said gateway.

2. A structure as claimed in claim 1 wherein the plates are dished.

PAUL HAHN.
